UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR BUSHING AND MEANS FOR SUPPORTING CORES OR BAFFLES THEREIN.

Application filed August 11, 1924. Serial No. 731,502.

This invention relates to insulator bushings for high potential conductors and has for its object the provision of a bushing of improved construction and operation and 5 which shall have improved means for supporting internal baffles or cores therein.

The invention is exemplified in the combination and arrangement of parts shown in the accompanying drawings and described 10 in the following specification and it is more particularly pointed out in the appending claims.

In the drawings—

Fig. 1 is an elevation with parts in section 15 showing one embodiment of the present invention.

Fig. 2 is a section on line 2—2 of Fig. 1.

In high voltage bushings where it is desired to have little or no surface charging 20 current until a very high voltage is reached, it is highly desirable to construct the bushings in two parts using an internal electrostatic screen to suppress charging current, tending to start from the flange. Bushings 25 of this type are usually constructed with two dielectric shells which form the outer contour and a center nest of baffles with the intervening space between baffles and outer shells filled with insulating oil or compound. 30 One of the most difficult problems in bushings of this kind is to support the baffles and not destroy the effective tightness of the outer chamber formed by the shells.

Fig. 1 shows a type of construction which 35 is very effective for overcoming these difficulties and for maintaining an efficient bushing at relatively low cost. Fig. 1 shows one form of the invention and Fig. 2 shows a section on line 2—2 of Fig. 1.

It is evident that the bushing may have 40 weather sheds or flanges at either or both ends or may be entirely smooth, depending upon the use for which the bushing is desired. In Fig. 1 the bushing consists of an upper dielectric member 10, a lower dielectric member 11 assembled or attached to holding flanges 12 and 13 respectively. The two portions are made tight by a gasket 14 which is clamped tightly by the bolts 15. A conductor 16 extends through the center of the bushing and terminates in the members 17 and 18.

In the form shown, the twisted conductor may have sufficient resiliency to provide for differences in expansion between the conductor and the dielectric shells, or it may be assembled so as to be slack. If either of the constructions are involved, it is not necessary to support the baffles 19 and 20 except from the main outer shell members. The baffles 19 and 20 are held together by a joint 21 which may be a suitable cement or cushioning material such as cork squeezed into the space between the two members. Where cement is used, it is desirable to use a resili- 55 ent type of joint such as that shown in my prior Patent No. 1,284,975. Where a cushioning material such as cork is used it is generally advisable to use a varnish which 60 will cause the cork to adhere firmly to the surfaces when dry or when baked. In order to prevent charging current flowing over the surfaces of the dielectric shells 10 and 11 from the metallic holding members 12 and 13, it is usually desirable to insert an electro- 65 static screen 22. In order to be effective, this screen must have considerable capac- 70 itance between it and the metallic members 12 and 13 or be in direct contact with them. 75

In Fig. 1, contact between the electro- 80 static shield 22 and the holding member 13 is made through a spring or lead 23 which is inserted in the gasket 14. This contact is made between the member 23 and a thin metallic dam 24, immediately on the inside 85 of the shell. The metallic dam 24 makes contact either through the bolt 15 or by having the end turned under the lower half of the gasket. The spring or contact member 23 being thin may be readily clamped in the 90 gasket, which is preferably made in two or three layers, without destroying the tight- 95 ness of the joint. If the electrostatic screen 22 is used to hold the center baffles as in some cases, a rather heavy metallic member 95 must be used which is inserted in the joint or by attaching directly to a flange or sleeve. This tends to subject the members of the shell to mechanical stress due to different expansion and tends to destroy the tightness of the 100 joint.

In the construction shown, it is possible to clamp the dielectric members directly together with only a small gasket of yielding

material intervening. The construction adopted also, makes it unnecessary to use an intervening sleeve for holding purposes or to project below the oil level. By the elimination of the intervening sleeve the objection due to different expansion is not only removed but a greater amount of surface insulation is provided for the lower member for a given length below the flange with 10 out danger of static discharge over the lower end of the bushing as this is prevented by the static screen 22. Since the dielectric members or baffles 19 and 20 are likely to have considerable weight and may be fragile, suitable means must be provided for holding them in place. In order to hold the baffles or cylindrical dielectrical members, spacers 25 are inserted between the baffles and the members composing the outer 20 shell. These spacers are preferably of a yielding material such as cork, mineral felt or rolls of varnished cambric or tape or even wooden spacers. The material 25 used for holding, should have vents 26 as shown in 25 Fig. 2. This permits the escape of entrapped air in filling with oil or compound and also, permits the circulation of the oil so as to maintain a fairly uniform temperature on all parts of the bushing and to provide 30 for carrying away the heat generated in the conductor.

The spacing or holding members 25 may be attached by varnish or other suitable means to the shells or to the baffle member 19. Since the members 19 and 20 are held together mechanically, it is evident that the holding member 25 may be applied between the shell and the member 20 in place of the member 19 by suitably forming the parts. 40 Where the holding member 25 has practically the same insulating properties as the filling oil or compound, the distribution of stress and performance of the bushing will not be affected and the performance will be 45 equivalent to that where no holding member is used.

The construction results in a bushing having relatively light weight, high dielectric strength, freedom from static or surface 50 charging current and one which may be readily assembled or disassembled should a part become accidentally or otherwise damaged.

The construction is such that the dielectric stress is taken up not only by the dielectric 55 members 19 and 20 but by the oil or compound in the spaces 27, 28 and 29. The cement or holding means 21, between the baffles, is provided with vents 30 shown in Fig. 2. Since it is not necessary to support 60 the baffle system by the center conductor, a flexible conductor having resiliency may be used which avoids the necessity of expansion joints at the upper end, thereby simplifying the construction. Vents 31 are provided to

relieve the bushing from internal expansion. 65 No expansion chamber is necessary, owing to the continuous upper shell which permits the use of an air space in the upper section without affecting the efficiency of the bushing.

An expansion chamber may of course, be used, as is common practice, with oil or compound filled types. Entrance may also, be made through the joint for controlling the height of the oil or compound.

I claim:

1. An insulator bushing comprising a pair of shell members, means for clamping said shell members together to form a closed casing, a cylindrical baffle arranged within said casing and over-lapping the joint between said shell members, and spacers interposed between said baffle and the interior of said shell members to support said baffle within said casing, said spacers being arranged to provide openings between said baffle and the casing to permit circulation of material within said casing.

2. An insulator bushing comprising an elongated casing of dielectric material, a plurality of concentrically arranged cylindrical baffles within said casing, means connecting adjacent faces of said baffles but providing circulation openings therebetween and spacers for supporting the outermost one 95 of said baffles from the inner surface of said casing, said spacers being arranged in circumferentially spaced relation to one another to provide openings for the circulation of material within said casing.

3. An insulator bushing comprising a pair of shell members having open ends arranged to register with one another, said shell members being tapered inwardly from said open ends, means for clamping said shell members together to form a closed casing, a cylindrical baffle disposed within said casing and over-lapping the joint between said shell members, packing material for supporting said baffle within said casing and providing 110 openings for the circulation of material within said casing, a second cylindrical baffle arranged within said first baffle in spaced relation thereto, and having one end thereof projecting beyond the end of said first named 115 baffle and means for supporting said second baffle from said first baffle.

4. An insulator bushing comprising an outer dielectric casing, a baffle within said casing and supported directly therefrom 120 and a flux screen of conducting material arranged within said casing and supported from said baffle.

5. An insulator bushing comprising a hollow casing of dielectric material, a hollow 125 cylindrical baffle of dielectric material disposed within said casing, means for supporting said baffle from the interior of said

- casing and a flux screen of conducting material supported on the outer face of said baffle.
6. An insulator bushing comprising a pair of dielectric shell members, means for clamping said shell members together to form a closed casing, a cylindrical baffle having supporting bearings upon the inner surface of said casing and arranged in over-lapping relation to the joint between said shell members, a flux screen of conducting material supported on the outer surface of said baffle and means extending through the joint between said shell members for making electrical connection with said flux screen.
7. An insulator bushing comprising a pair of shell members having open ends arranged to register with one another, a flange secured to the outer face of one of said shell members adjacent its open end, means for clamping said shell members together to form a closed casing, a cylindrical baffle of dielectric material arranged within said casing and having supporting bearings on the inner surfaces of said shell members, a cylindrical flux screen surrounding said baffle and supported thereby and means extending through the joint between said shell members for forming an electrical connection with said flange and flux screen.
8. An insulator bushing comprising a pair of dielectric shell members having open ends arranged to register with one another to form a casing, metallic flanges secured to said shells adjacent said open ends, means for clamping said flanges together to hold the ends of said shells in abutting relation, packing material interposed between said ends, a flux screen arranged within said cas-
- ing, and electrical connection between said screen and flanges extending through the packet joint between said abutting ends.
9. An insulator bushing comprising a pair of dielectric shell members having open ends, means for clamping said shell members to one another to form a closed casing, a cylindrical baffle of dielectric material arranged within said casing and having the ends thereof seated respectively on the interiors of said shell members, a flux screen surrounding said baffle and supported thereby and a covering of dielectric material for the edge of said screen.
10. An insulator bushing comprising a pair of dielectric shell members having open ends arranged to register with one another, a metallic flange secured to one of said shell members, means for clamping said shell members together to form a closed casing, a conductor extending centrally through said casing, a cylindrical baffle of dielectric material having opposite ends thereof seated upon the interior of said shell members respectively, a second baffle within said first named baffle and surrounding said conductor, means forming a supporting connection between said baffles but permitting circulation therebetween, a metallic flux screen supported on the outer face of the outermost baffle, insulating material arranged to cover the edges of said flux screen and electrical connection between said baffle and said flange.

In testimony whereof I have signed my name to this specification on this 4th day 75 of August, A. D. 1924.

ARTHUR O. AUSTIN.
